UNITED STATES PATENT OFFICE.

JAMES D. MCCOY, OF BOSTON, MASSACHUSETTS, ASSIGNOR TO UNDERWOOD TYPE-WRITER COMPANY, OF NEW YORK, N. Y., A CORPORATION OF DELAWARE.

TYPE-WRITING MACHINE.

1,290,764.

Specification of Letters Patent.

Patented Jan. 7, 1919.

Application filed November 8, 1917. Serial No. 200,872.

To all whom it may concern:

Be it known that I, JAMES D. MCCOY, a citizen of the United States, residing in Boston, in the county of Suffolk and State of Massachusetts, have invented certain new and useful Improvements in Type-Writing Machines, of which the following is a specification.

This invention relates to an improvement in a collating device for assisting in assembling in various relations a plurality of work-sheets upon the platen.

For the purpose of bringing the sheets into such relative positions that selected lines on the several work-sheets coincide with each other, the lines being located at different points upon the several sheets, there is provided a collating table supported to revolve with the revoluble platen. The table is so located as to form a continuation of the platen at the front thereof, whereby the sheets can be inserted on the platen and fed past the same to a position on the collating table, where their relative arrangement can be determined, while the sheets remain bent round the platen and in position to be gripped by the feed rolls that usually run upon the bottom of the platen.

The collating table is provided with a gage, whereby the leading edge of the bottom work-sheet may be positioned, so that for a selected blank line will be the first to be typed upon.

Clamps are provided for holding this work-sheet on the table while assembling her work-sheets thereupon. These clamps do not require the use of previously made notches in the work-sheets. The clamps are adjustably mounted upon rails located at the side of the table, so that when clamp has been swung into its effective position, it can be slid from one work-sheet another as they are successively assembled on the table. Or the clamps may be alternately swung into effective positions, one holding the first sheet while the other is being away to permit the second sheet to be superposed, said second sheet then being held by the idle clamp which is swung down to hold both sheets, the first clamp being swung up to permit insertion of third sheet, and so on.

A leading-edge gage is mounted upon one

of the clamp-supporting rails, and may be used to locate the other sheets after the first sheet has been placed on the table. This gage may be adjustable, to be positioned at various points along the side rail, by the aid of a scale provided on the side of the table.

Other features and advantages will hereinafter appear.

In the accompanying drawings,

Figure 1 is a perspective view, showing the collating table in position above the platen with several of the work-sheets collated thereon.

Fig. 2 is a vertical section, taken from front to rear, showing an end view of the collating table.

Fig. 3 is a front view in elevation with parts broken away to show the underlying structure.

Fig. 4 is a vertical section, taken from front to rear through the collating table.

Fig. 5 is a detail section, taken from right to left of the table and looking from front to rear of the plane of the table. This view shows the auxiliary scale in its operative position and close to the back of the table, and also shows one of the clamps in its inactive position.

A platen 1 is mounted to rotate on a frame 2, which may travel with the typewriter carriage in the usual manner. The platen may be rotated by means of line-space mechanism 35 3 or hand-knobs 4, as common to the standard Underwood typewriter, for the purpose of line-spacing work-sheets as they are fed past a printing point, indicated by a type-bar 5. The work-sheets upon the platen 1 90 are advanced by means of the usual pressure feed rolls 6 running upon the bottom of the platen. This Underwood mechanism includes a train of linkages 7 connected to a release 8, whereby the rolls may be cast off 95 and restored.

A paper-apron 9 delivers the work-sheets to the platen 1, whence they are guided forwardly under the platen by a paper-shield 10, which cooperates with the rolls 6 in holding the work-sheets on the platen.

When a number of work-sheets of different type are to be simultaneously typed, generally at lines located at different distances from the leading edges of the several sheets, it is necessary first to assemble or

collate the sheets. For this purpose, there is provided a collating table 11, which is supported so that its lower edge 12 is close to the platen 1 at the front thereof. This enables the table to form a practical continuation of the surface of the platen 1, whereby the work-sheets as inserted on the platen may be extended up over the table 11 and their relative positions adjusted with the aid of the table 11, while they extend between the platen and the bottom feed roll 6. To support the table 11, there is provided on the platen frame 2 side brackets 13. The brackets 13 support a frame 14 to which the table 11 is secured. The means of securing the table 11 to the frame 14 includes set-screws 15, which are inset in depressions 16 provided in the supporting surface of the table, to permit free travel of the sheets over the surface of the table.

The first or lowermost sheet in the pack, which is generally the ledger sheet and the longest, may be positioned on the table 11, so that its leading edge is brought up against fixed gages 17 provided on the upper edges of the table 11, the back of the table being cut away at its central portion to form separated supporting surfaces. When the ledger sheet is placed upon the table 11, one or both of a pair of clamps 18 and 19 may be brought into engagement with the work-sheet, so as to hold it on the table 11. These clamps merely grip the work-sheet to the table, and preferably do not perforate or puncture it.

Each of the clips or clamps 18, 19 is pivotally mounted on a rail 20, so that it can be swung from an inactive position, illustrated in Fig. 5, to an active position, illustrated in the remaining figures. The clip may be locked in its two positions of adjustment by means of a roller 21, which is forced into engagement with the rail 20 by means of a spring 22. When the clip is in its active position, the roller 21 engages in a groove 23 extending lengthwise of the rail 20. The grooves 23 extend along the entire length of the rails 20, and are so placed relatively to the rollers 21 that the clips 18, 19 will be pressed onto the collating table by the springs 22 when the rolls 21 engage the grooves 23. The grooves 23 enable the clips to be adjusted along the rails, and thus adjusted lineally relatively to several work-sheets.

Each clip 18, 19 includes a slide 24, upon which the roller 21 and spring 22 are supported. This slide 24, in turn, supports an arm 25 to which a bracket 26 is secured. The bracket 26 forms a mounting for a roller or other suitable pressure device 27, which directly engages the work-sheet or sheets and holds them temporarily in position on the table 11. The clip 18, 19 may be provided with a finger-grip 28, whereby

it is swung between active and inactive positions. The arm 25 of each clip may be arched to avoid the side-gages or guides 25^a of the table 11, so that the pressure device 27 may properly engage work-sheets on the table 11 while the rails 20 are located below the top edges of the sides of the table. This makes a compact structure.

To determine the positions of the succeeding work-sheets after the first, which in the present case is shown as the ledger sheet, there may be provided on the ledger sheet a series of indications 29, which correspond to the several lines of typewriting. The other sheets may be provided with corresponding indications, or their positions may be determined by bringing their leading edges in register with the indications on the ledger sheet. To take care of the assembling of the succeeding work-sheets, and in some cases the first work-sheet, a leading-edge gage 30 is provided. This may be slidably mounted for adjustment up and down upon one of the rails 20. There may be one of these gages 30 on each side of the table 11 if desired. The gage 30 is mounted on the rail 20 similarly to the clips 18 and 19, so that it can be swung about its supporting rail between active and inactive positions, and can also be slid along the rail for different gaging positions. The gage 30 has a structure somewhat similar to that of the clips 18 and 19, and is provided with a spring-pressed roll-lock similar to the lock 21, 22. The position of the gage 30 may be determined by means of a scale 31 inscribed upon the adjacent side of the table 11. The gage 30 may cooperate with either side-gage 25^a to square the sheet to the platen.

The clips 18 and 19 may be used for indicators as well as clips, and are pointed for this purpose. They may be adjusted to the number or other indication provided either on the work-sheet or sheets, or the side of the table.

The work-sheets are assembled by placing them one at a time upon the platen 1 after the pressure feed rolls 6 have been released, and drawing them up different distances over the table 11. The longest sheet may be used as a gage for the other sheets, by bringing its leading edge up against one of the fixed gages 17. If this sheet is not long enough to remain upon the platen 1 and still reach the fixed gage 17, its position may be determined with the aid of the scale 31 (upon gage 25^a) and the auxiliary adjustable gage 30. The other sheets may be placed upon the platen 1 with the interleaved carbon sheets and drawn up different distances across the table 11, so as to bring the next line to be written on the several sheets in superposed register with each other. The clips 18, 19 may be shifted to engage the sheets *seriatim* and hence used

- to hold each sheet on the table as the sheet is drawn up to the extent desired, without releasing the previously collated sheet or sheets, so that the operative will have his hands free to introduce and adjust other work-sheets. As the clips 18 and 19 are adjustable along the rails 20, they may be used to hold sheets differently-extended over the table 11.
- 16 When all of the sheets have been assembled in their several relative positions, the pressure feed rolls 6 are brought into play, so as to grip the assembled pack of sheets to the platen 1. The clips 18 and 19 can then be swung to their inactive positions of Fig. 5, and the collated pack of sheets may be drawn back upon the platen by a reverse rotation thereof until the initial line to be written on is brought into register with the printing point of the typewriter. It will be noted that the clips 18 and 19 and the auxiliary gage 30 can be swung out of the way, so as to be clear of the work-sheets as they come up over the table 11, allowing them 25 to have a free passage, so that their movement will be uninterrupted.

Since the ledger sheet used for bookkeeping purposes is actually wider than the statement-sheet which is typed at the same time as the ledger sheet, it follows that the ledger sheet is placed upon the statement-sheet would be apt to cover up the latter entirely. It will be seen, however, that my invention provides convenient means whereby this superposition of the ledger-sheet upon the statement-sheet may be practised, so that the ledger sheet may receive the ink ribbon impressions, which is a desideratum. The statement-sheet may be adjusted by either side gage 25^a, and the end gage 30, and then held in such position by the collating clip 27, while the ledger sheet is being adjusted to the opposite side gage 25^a and to the leading-end gage 17; the ledger sheet not being quite wide enough to reach said collating clip. The other collating clip may now be brought into use to hold the ledger sheet. Then the bottom feed-rolls 6 may be brought into use to clamp both sheets against the platen; whereupon both collating-clips 27 may be cast off.

Since the leading-end gage 30 is useful not only in writing statements, but may also be used in aligning letters and other work-sheets when the machine is not being used for bookkeeping, said end gage is made adjustable so that it may serve for various kinds of work-sheets, as well as serving in the collating operation for locating one of the sheets mechanically.

The various features of the invention are capable of still other uses in the bookkeeping art.

Variations may be resorted to within the scope of the invention, and portions of the

improvements may be used without others, as for example the gage 30 may be omitted as at Fig. 1.

Having thus described my invention, I claim:

1. The combination with a revoluble platen having a feed-roll, of a relatively fixed collating table mounted at the delivery side of the platen in a position to serve for collating the work-sheets thereon while they extend between the platen and feed-roll, and means to cooperate with said table to hold sheets against advance movement, said co-operating means including means to clip the sheet to the table, said clipping means releasable to permit the collated sheets to travel around the platen, said clipping means also shiftable in the direction of travel of the work-sheets relatively to said table. 70 75

2. The combination with a revoluble platen having a feed-roll, of a relatively fixed collating table mounted at the delivery side of the platen in position to serve for collating work-sheets thereon while they extend between the platen and feed-roll, and 80 85 means to cooperate with said table and movable to engage a work-sheet newly collated thereon while detaining a sheet or sheets previously collated upon said table; said holding means effective to prevent edgewise movement of the sheets, and releasable to permit advance of the sheets. 90 95

3. The combination with a revoluble platen having a feed-roll, of a relatively fixed collating table mounted at the delivery side of the platen in position to serve for collating the work-sheets thereon while they extend between the platen and feed-roll, and means to cooperate with said table to hold one or more sheets against advance movement upon said table while another sheet is being collated thereon, said co-operative means including a plurality of clips mounted at the sides of said table and each releasable while the other clip or clips hold the previously placed sheet or sheets, each clip independently shiftable in the direction of travel of the work-sheets relatively to said table. 100 105 110

4. The combination with a revoluble platen having a feed-roll, of a relatively fixed collating table mounted at the delivery side of the platen in position to serve for collating the work-sheets thereon while they extend between the platen and the feed-roll, and means to cooperate with said table to engage and detain newly collated sheets while detaining previously collated sheets against movement, including a rail mounted on said table at right angles to the platen and a clip slidingly and pivotally mounted on said rail to slide along said rail from sheet to sheet and to swing up to release the sheets. 115 120 125

5. The combination with a revoluble

1. The combination with a platen, of a feed-roll, of a relatively fixed collating table mounted at the delivery side of the platen in a position to serve for collating the work-sheets thereon while they extend between the platen and feed-roll, and means shiftable from sheet to sheet to coöperate with said table to detain each newly collated sheet without releasing the previously collated sheets, said means comprising a releasable clip mounted upon said table to be adjustable to all positions of work-sheets along said table.

6. The combination with a platen, of a collating-table having a side gage and mounted to travel with said platen and arranged in juxtaposition to the upper front of said platen, so as to collate work-sheets while said work-sheets are on said platen, a fixed leading-edge gage on said table for coöperating with certain of said work-sheets, and an adjustable gage movable in the direction of travel of work-sheets and universal to the length of said table in the direction of travel of said work-sheets, said adjustable gage coöperating with said side gage and supplementing said fixed gage in collating work-sheets with their leading edges at different positions along the travel of work-sheets on said table; said table provided with means for detaining the sheets as they are collated to said leading edge gages.

7. The combination with a platen, of a collating-table coöperating with said platen to assemble work-sheets for said platen, a rail mounted on said table, a clip slidably and pivotally mounted on said rail to temporarily hold work-sheets on said table while being collated, and a gage for said work-sheets slidably and pivotally mounted on said rail to move between active and inactive positions, and to different active positions along said rail, and in the direction of movement of work-sheets on said table.

45. 8. The combination with a revolute platen having a feed-roll, of a relatively fixed collating table mounted at the delivery side of the platen in a position to serve for collating the work-sheets thereon while they extend between the platen and feed-roll, means shiftable from sheet to sheet to coöperate with said table to detain each newly collated sheet without releasing the previously collated sheets, said means comprising a releasable clip mounted upon said table to be adjustable to all positions of work-sheets along said table, and an indicator for aiding to locate the work-sheets upon the table.

60. 9. The combination with a revolute platen having a feed-roll, of a relatively fixed collating table mounted at the delivery side of the platen in a position to serve for collating the work-sheets thereon, a side gage

for said table, an adjustable leading-end gage for said table against which to gage the leading end of a sheet while it extends between the platen and feed-roll, and releasable means to coöperate with said table to secure against edgewise movement the sheets as they are collated one by one thereon.

10. The combination with a revolute platen having a feed-roll, of a relatively fixed collating table mounted at the delivery side of the platen in a position to serve for collating the work-sheets thereon, a side gage for said table, an adjustable leading-end gage for said table against which to gage the leading end of a sheet while it extends between the platen and feed-roll, and releasable means to coöperate with said table to secure against edgewise movement the sheets as they are collated one by one thereon, said adjustable gage being mounted for movement out of working position.

11. The combination with a revolute platen having a feed-roll, of a relatively fixed collating table mounted at the delivery side of the platen in a position to serve for collating the work-sheets thereon, a side gage for said table, an adjustable leading-end gage for said table against which to gage the leading end of a sheet while it extends between the platen and feed-roll, and releasable means to coöperate with said table to secure against edgewise movement the sheets as they are collated one by one thereon, said leading-edge gage mounted at one side of said table for movement out of working position, and said collating table being also provided at the other side thereof with a permanent leading-edge gage.

12. The combination with a revolute platen having a feed-roll, of a relatively fixed collating table mounted at the delivery side of the platen in a position to serve for collating the work-sheets thereon, a side gage for said table, an adjustable leading-end gage for said table against which to gage the leading end of a sheet while it extends between the platen and feed-roll, said leading-edge gage being mounted at one side of said table and movable out of working position, and said table being provided at the other side thereof with a permanent leading-edge gage, and a clip to coöperate with said table to hold the sheets against edgewise movement, said clip releasable to permit advance of the sheets.

13. The combination with a revolute platen having a feed-roll, of a relatively fixed collating table mounted at the delivery side of the platen in a position to serve for collating the work-sheets thereon while they extend between said platen and feed-roll, a side-edge gage for said table, means at one side of the table for clipping the sheet or sheets thereon while the sheets are at various positions between the top and bottom of

120

125

130

- the platen, and independently operable sheet-clipping means mounted at the other side of the table; all of said sheet-clipping means coöoperative with said table to hold the sheets 5 against edgewise movement, and also releasable to permit advance of the sheets.
14. The combination with a revoluble platen having a feed-roll, of a relatively fixed collating table mounted at the delivery 10 side of the platen in position to serve for collating the work-sheets thereon while they extend between the platen and feed-roll, and means to coöperate with said table to hold 15 one or more sheets against advance movement upon said table while another sheet is being collated thereon, said coöperative means including a plurality of clips mounted at the sides of said table to hold the sheets against edgewise movement and 20 each releasable to permit the introduction of a sheet while the other clip or clips hold the previously placed sheet or sheets, and also to permit advance of the sheets.
15. The combination with a revoluble platen having a feed-roll, of a relatively fixed collating table mounted at the delivery 25 side of the platen in position to serve for collating work-sheets thereon while they extend between the platen and feed-roll, means 30 to coöperate with said table and movable to engage a work-sheet newly collated thereon while detaining a sheet or sheets previously collated upon said table, said means 35 including a rail extending along said table in the direction of movement of said work-sheets across said table, and a collating clip
- slidingly mounted on said rail, and means to cooperate with said clip to enable it to hold the sheets against the table and to slide along said rail while in engagement with 40 the sheets.
16. The combination with a revoluble platen having a feed-roll, of a relatively fixed collating table mounted at the delivery 45 side of the platen in a position to serve for collating the work-sheets thereon while they extend between the platen and feed-roll, and means shiftable from sheet to sheet to coöperate with said table to detain each newly collated sheet without releasing the previously 50 collated sheets, said means comprising a pair of independently releasable clips mounted at opposite sides of the table, each to be adjustable independently of the other to all positions of work-sheets along said 55 table.
17. The combination with a revoluble platen and a feed-roll therefor, of a collating table relatively fixed and mounted at the delivery side of the platen, said table 60 provided with a permanent leading-edge gage to gage sheets which extend between the platen and feed-roll, and a second gage mounted on said table between said permanent gage and the platen, said second gage 65 being mounted for movement to an ineffective position, and adjustable relatively to the printing line on the platen.
